(57) **CLAIM**

The ornamental design for an engine cylinder multi-port exhaust arrangement, as shown and described.

DESCRIPTION

FIG. 1 is a perspective view of an engine cylinder multi-port exhaust arrangement, showing my new design;

FIG. 2 is a front elevational view thereof;

FIG. 3 is a left-side elevational view thereof;

FIG. 4 is a right-side elevational view thereof;

FIG. 5 is a top plan view thereof; and,

FIG. 6 is a bottom plan view thereof.

The dot-dash broken lines in the figures represent a boundary of the claimed design, elements of the engine cylinder multi-port exhaust arrangement outside of the boundary in regular broken lines forming no part of the claimed design, and the regular broken lines within the circular element in FIGS. 1 and 5 form no part of the claimed design.
